Application April 30, 1930. Serial No. 448,740

4 Claims. (Cl. 263—21)

This invention as indicated relates to a method and apparatus for metal working and product resulting therefrom. This application is a continuation in part of my application Serial No. 5 99,482 filed April 3, 1926, part of which matured into United States Patent No. 1,659,445, granted February 14, 1928, and for which divisional and continuing applications are copending herewith. More particularly the invention relates to the 10 method of and apparatus for working metal while in a molten condition in a furnace chamber, in such manner that the same may be de-oxidized and mechanically worked upon so as to improve the grain and fiber of the metal, free 15 from impurities and entrapped particles of foreign matter, and improve the density and physical characteristics of the final product. The apparatus is especially adapted for the remelting of secondary material and preparing the 20 same in a single continuous operation for fabrication into articles of high quality. It may be used particularly with such metals as are readily oxidized, such as aluminum, but is also suitable for the treatment of other metals and may be 25 used to advantage in the formation of alloys of various character. It is readily adaptable for use with aluminum or alloyed borings, turnings, sawings, filings, skimmings, drosses, or the like, and may be used with material such as this for producing 30 metal suitable for commercial fabrication into castings as a single continuous operation. The material may be cast into ingots, if desired, or may be fed back through the furnace chambers after withdrawing from the casting side of 35 the furnace with any desired additions of material necessary to form a predetermined alloy. The method includes the reworking of aluminum stock of finely divided character such as is known commercially as "salvage" or "secondary" metal 40 which stock frequently is mingled with oils and greases and particles of iron, and often includes material heavily oxidized. The invention includes a furnace with agitating mechanism. To the accomplishment of the foregoing and related 45 ends, said invention, then, consists of the means, method and product hereinafter fully described and particularly pointed out in the claims.

The annexed drawings and the following description set forth in detail certain means and 50 one mode of carrying out the invention, and one product resulting therefrom, such disclosed means, mode and product illustrating, however, but several of various applications of the principle of the invention.

55 In said annexed drawings:

Fig. 1 is a side elevation partially in section of a furnace installation embodying the principle of my invention; Fig. 2 is a top plan view of the apparatus shown in Fig. 1; Fig. 3 is a sectional plan view of the furnace proper; Fig. 4 is a side elevation of the grid; Fig. 5 is a top plan view of the grid; Fig. 6 is an enlarged sectional detail view showing the grid attaching means; Fig. 7 is a side elevation partially in section of a modified type of a furnace somewhat similar to that shown 60 in Fig. 1 wherein a communicating chamber is provided on each side of an agitating chamber; Fig. 8 is a plan view, partially in section, of the apparatus shown in Fig. 7; Fig. 9 is a plan view of a modified form of furnace structure; and Fig. 70 10 is a top plan view of a modified form of grid.

As is clearly shown in Figs. 1 and 3 of the drawings, the furnace 1 comprises a brick structure formed of piers and arches and providing for each furnace unit, two closed furnace chambers 75 2, 3, separated by a heavy brick wall and communicating with each other through a small conduit 4 adjacent the floor of said chambers. The reservoir sections of said furnace unit are shown as of substantially equal size although the proportions may be varied in accordance with special requirements or with the character of the stock and the rate of use of the product or other conditions. At a point above the level of the molten metal in said chambers, charging and 80 skimming doors are provided.

While a single furnace unit might be provided, it has been found more economical to construct three or more furnace units in series in a single structure, as shown, which may be simultaneously operated by a crew of workmen more economically than a single furnace unit or a series of independent furnaces. Likewise the operating mechanism for a series of furnace units may be more economically installed and the heat losses 95 may be proportionately reduced. In the drawings, therefore, I have illustrated three furnace units in series. The units are each operatively distinct from the others and a different alloy may be run in each chamber.

100 Each of said units is divided centrally by a partition wall 5 so as to provide on one side a combined charging and agitating chamber 2 through which the metal stock is fed into the furnace and on the opposite side with a heating 105 chamber 3 for the reception and temperature control of the casting supply of molten metal.

The dividing wall 5 preferably extends from the ground to the roof of the furnace. Beneath each of the series of chambers 2, 3, arched heat- 110

ing chambers 6, 7, extend. The floors 8, 9, of the communicating chambers 2, 3, rest upon these arches and are packed with ganister or other heat resisting material, and the walls of said chambers 5 are formed of or lined with firebrick. Where a series of three furnace units is provided, it is found more economical of fuel to have the division walls between the several charging sections and likewise the walls between the several 10 casting sections extend only to a point slightly above the side doors so that the gases in the upper part of the furnace on the respective sides of the dividing wall 5 may travel freely into any one of the three adjacent charging chambers or 15 the three adjacent casting chambers. Centrally of the outer wall of each of the charging chambers a charging opening 11 adapted to be closed by a sliding charging door 12 formed of fire brick, is provided.

20 Centrally of the outer wall of each of the series of the casting chambers an opening 13 is provided adapted to be closed by a sliding firebrick door 14. Within the upper open portion of the series of casting chambers, a fuel supply 25 nozzle (not shown) is provided through which atomized crude oil or some such fuel mixture may be projected into the casting chambers. Counterweights (not shown) may be individually applied to each of the doors of the several charging and casting chambers so that the same may 30 be readily lifted and lowered when the furnace is in operation. In addition to the fuel supply charged directly into the upper portion of the casting chambers above the metal reservoirs, provision is made for the heating of each of said 35 series of furnaces by means of nozzles (not shown) within one end of the arched chambers 6 and 7 heretofore described. An opening 10 is provided at the end of the chamber 7 to permit egress of 40 excess hot gases at that end of the furnace, and this lower opening also constitutes a safety overflow in the event of a leak in the metal reservoirs.

45 On the discharge or casting side of the furnace, a tap hole 15 and spout 16 is provided adjacent the central lower portion of each of the metal reservoirs. Along each lateral side of the furnace tanks or troughs 17, 18, adapted to be filled with water are provided into which hot skimmings from the top surface of the molten 50 metal may be dropped as the occasion arises. The depositing of the skimming in the troughs separates the aluminum from the dirt and the aluminum may be again used as part of a charge for the furnace.

55 At each end of the charging side of the series of furnace units adjacent the top arch an opening 21 is provided, over which a door 22 lined with fire brick is hung, and through which the furnace gases carrying light dust and dirt and the burning particles of grease and oil, which 60 may be mingled therewith, partially escape. These doors also serve as safety or "explosion" doors and prevent undue pressure within the furnace.

65 It will be noted that above the surface of the molten mass of metal the furnace carries a heavy tank of hot gases which are sufficient in quantity to completely fill the space referred to and that such gases are at a slightly higher pressure than 70 the outside atmosphere and constantly seek a passageway through the end openings on the charging side of the furnace heretofore described. Thus when metal stock is charged through any of the several openings into the charging chambers, but little air enters at such points because

80 of the higher pressure of the gases within the furnace which seek egress at such time. Each of the end and internal walls of both the charging and casting chambers is provided with a flue (see Fig. 3) respectively through which the gases of combustion may pass in part, thus maintaining the temperature of the furnace walls at the desired point. The flues on the casting side are ordinarily left open but the flues on the charging side are kept closed by covers inasmuch as the lower heating chamber 8 is only intended for emergency use, at times when the furnace charge might freeze and require a high degree of heat to remelt.

85 The means for agitating the molten mass of metal on the charging side of the furnace will now be described and while a particular embodiment of such apparatus is illustrated, it is to be understood that other mechanism for accomplishing the same result may be employed instead of that illustrated. Within each of the charging chambers a grid or stirring member is provided which is of an outline similar to that of the furnace chamber and of slightly smaller size than said chamber. Said member 90 comprises a heavy central portion or boss, 32, and a series of radial arms 33 gradually decreasing in thickness toward their free ends and joined at such ends by a rim 34 of metal corresponding in outline to the outline of the furnace chamber and spaced from the walls thereof. Between the radiating arms spaces are provided through which the molten metal may freely pass as the grid is plunged downwardly into the molten metal and withdrawn therefrom by the 100 mechanism presently to be described.

95 Centrally of the grid a beveled socket 36 is provided through which the lower end of the operating stem 37 of the agitating device may be received. The lower end of the stirring rod 105 or operating member is provided with notches 38 to receive projections 39 upon a series of shoes 41 which have beveled sides 42 terminating in outwardly extending flanges, 43. In order 110 to engage the grids with the operating rods, the lower ends of said rods are inserted through the central apertures of said grids and the shoes or tapered plates are engaged with said rods and the grid lowered on the outer beveled surfaces of said plates. The beveled surfaces on the 115 grid aperture and on the outer side of the respective plates coact to insure a firm engagement of the grid with the rod. The rod may be supplied in two sections which are joined to each other in a spliced joint 44 providing 120 a pair of shoulders and overlapping extensions of half the rod size which are firmly bolted together. A boot 40 packed with fire clay and strapped about each rod above the grid prevents the burning out of the rod as it is plunged 125 into the molten mass of metal.

130 Each of the rods is engaged through an aperture 45 in the roof of the charging side of the furnace so as to reciprocate therein with a minimum loss of heating gases therethrough. Above the furnace said rods are each adapted to reciprocate between two pairs of rollers 46, 49, firmly mounted upon a supporting frame 48 so as to maintain said rod in constant alignment 135 with the aperture through said furnace roof. These rollers are preferably flanged rollers engaging in pairs on opposite sides of the square operating rod and suitable lubricating device for said rollers may be provided. The rod is set 140

145 150

145 150

155 160

angularly to provide for easy removal of oxide and refuse or skimming.

The upper end of the rod is provided with an aperture 51 for attaching a lifting cable 52.

- 5 Adjacent the upper end of the rod an extension arm 53 is provided to which a grid depressing cable 54 is secured. The respective cables are passed about pulleys 55, 56, secured to fixed supports above the rod and adjacent 10 the roof of the furnace respectively and thence passed in opposite directions to a pair of sheave wheels 57, 58, mounted upon a shaft preferably located on a platform 61 above the level of the furnace roof. The shaft carrying the respective 15 pairs of sheave wheels is oscillated by suitable mechanism shown in this instance as an electric motor 62 coupled with a suitable reducing gear 63 to a crank arm 64 which is joined by a connecting rod 65 with a similar crank arm 20 66 on the oscillating shaft. The proportions of the parts are such that the shaft will be rotated through approximately 90° with each complete rotation of the first mentioned crank arm.

Each of the pairs of sheave wheels heretofore described is provided with a clutch member 25 67 on the oscillating shaft. The shifting bars (not shown) for the clutches are extended from the elevated platform to a position convenient to the furnace floor so that the operation of 30 the clutches may be readily controlled adjacent the charging side of the furnace. In addition to the sheave wheels heretofore described and the fixed pulleys, it is desirable to provide counterweights for the grids and supporting arms 35 and spring take-up means to prevent excessive strains upon the mechanism. Accordingly, a spring 71 is inserted in the line of the grid depressing cable and counterweight 72 is carried at the end of the grid elevating cable. The 40 counterweight is adapted to bear against a stirrup bar 73 supported on a pair of springs 74 which are secured to a fixed support 75 above the top range of motion of the counterweight so as to hold said bar in the path of movement 45 of the counterweight when the grid is drawn from the metal bath. The counterweights are guided upon a pair of bars 77 supported at each end in the frame of the operating mechanism and springs 28 on said bars serve as buffers. An adjusting pulley 81 is provided in the 50 line of grid elevating cable preferably supported on a pair of arms 82 pivoted to the frame at a point adjacent the sheaves and supporting said pulley rearwardly in alignment therewith. Each 55 of said pairs of frames is provided with a stationary nut 83 through which the upper end of a screw threaded rod 84 is adapted to engage. A hand-wheel is attached at the lower end of said rod whereby said pulley may be adjusted upwardly or downwardly to the necessary extent 60 to lift the grid to any point desired with respect to the liquid mass in the furnace chamber. Thus by turning the screw in one direction the grid may be fully withdrawn from the bath of liquid metal and held at a point above the charging opening of its furnace.

When adjusted in the opposite direction the grid may be forced to a considerable depth within the molten mass of metal as it reaches its lowest limit of motion in the charging side of the furnace. The spring provided in the grid depressing cable is put under tension as the grid is elevated and is relieved of the larger part of such tension when the grid is lowered to its usual operative position. It also serves as a

resilient safety device when the grid strikes an obstruction in its descent. Thus complete control of the agitating mechanism of the furnace is provided both as to the starting and stopping of the agitation and the position of the agitator with respect to the molten mass of metal may be readily adjusted. Through a suitable rheostat the motor speed of the operating device may be controlled and thus the rate of agitation may be regulated.

In the form of construction illustrated in Figs. 7 and 8, two puddling or agitating chambers 101, 102, are provided at a central position. Melting chambers 103 and 104 are provided respectively on the opposite sides of the agitating chamber 101, and melting chambers 105 and 106 are provided respectively on the opposite sides of the agitating chamber 102. Each of the melting chambers communicates with the adjacent agitating chamber through an opening 105, preferably adjacent the floor of said chamber. Each of the said melting chambers may be used, either, for introducing metal from large sections, such as castings or plates or ingots, and having the same flow into the casting chamber for the deoxidizing and refining action, or may be used to receive the treated mass of metal from the agitating chamber and temper the same to the proper degree of heat for fabricating purposes. The flow of the metal from either side may be controlled by 100 means of plugs inserted in the communicating openings and by the amount of material introduced into or withdrawn from the respective chambers and the chamber on either side of the puddling chamber may be used for the melting or 105 casting charge of metal as may be preferred. The construction and action of the agitating mechanism is substantially the same as that previously described in connection with the device illustrated in Figs. 1, 2 and 3. Each of the chambers adjacent the puddling chamber is provided with heating means (not shown) through which oil or other heating medium is introduced in the furnace to maintain the metal at the desired degree of temperature. The furnace is shown as 110 having an arch construction similar to that shown in Figs. 1 to 3, but obviously in either of the constructions the furnace may be built directly on the ground without heating or safety means beneath the furnace floor.

The agitating chambers 101 and 102 are open at their upper portions, the dividing wall 106 extending only to a point a short distance above the metal bath and approximately to a level of the base of the charging doors. The charging 130 doors 107, 108, are of a size to permit the withdrawal of the grid therethrough at either side. Each of the melting and charging chambers is provided with a draw-off hole 109 and a spout 111.

Each of the melting chambers is provided with a door 112 in the side wall and a door 113 in the end wall. The door in the end wall permits the plugging by means of a clay ball, or the like, of the opening from said chamber into the puddling chamber.

In the form of construction shown in Fig. 9 of the drawings, two puddling chambers, 114, 115, are shown centrally of one side of the furnace, and a melting chamber is shown in the space at the end of the furnace adjacent each of the respective puddling chambers. These melting chambers, 116, 117, communicate by means of an opening adjacent the bottom thereof with the puddling chamber, such opening 118 being adapted to be plugged from the end of the chamber 150

through a door in the end wall of such melting chamber. These end doors 119 may be used as the charging doors or metal charged into the melting chamber may be placed therein through the side doors 121. In addition to the melting chambers described, the furnace is provided with elongated melting chambers on the opposite side of the furnace. These chambers 122, 123, communicate with the agitating chambers through openings 124 adjacent the bottom of said chambers, and also communicate with the end melting chambers 116, 117, through suitable openings in the bottom thereof. The walls 125, 126, between the end and rearward melting chambers may extend only to a slight distance above the metal bath, so that the heat within the several melting chambers may extend continuously around the furnace. Suitable oil or gas burners may be employed to maintain the heat in the melting and casting chambers at any desired temperature. Suitable tapping holes and spouts may be provided adjacent the several chambers.

The apparatus disclosed in Figs. 7 and 8 is particularly suited for carrying on a continuous process of production of material suitable for commercial fabrication from readily oxidizable metals such as aluminum with a high degree of speed and great economy of manufacture, and permits of the addition of finely divided material directly into the puddling chamber and the addition of heavy scrap through one of the auxiliary chambers in connection with such puddling chamber. Thus all classes of commercial secondary sources of raw material for aluminum manufacture may be drawn upon and the supply of metal for the puddling and casting chambers may be kept up to requirement by drawing upon any stock which may be available at the particular time of use.

In each of the instances illustrated substantially the entire quantity of metal in the puddling chamber is acted upon by the grid which strikes the metal with a heavy impact and forces subdivided portions thereof through the apertures in the grid and carries loose particles through the interacting streams of molten metal and into the portions of the molten bath below the upper surface thereof so that the collected metal in the bottom of the puddling chamber may be brought into direct contact to freshly exposed particles of aluminum and envelop and incorporate the same directly into such body through coalescence.

The working of the metal in this way has a readily recognizable effect in improving the tenacity and strength of the fabricated material and the recovery of metal has been carried out commercially with as high or a higher degree of recovery than ordinary fire assay of samples will show because of the greater losses caused in the course of such assay through oxidation.

It will be noted that oxidation is prevented through the fact that the grease and oil and other combustible material carried with the charge of fine particles placed within the agitating chamber is carried on under conditions where-in complete combustion is not effected and therefore reducing gases such as carbon-dioxide, carbon monoxide, hydrogen, and other gases are held as a blanket at slightly greater than atmospheric pressure above the surface of the bath of molten metal undergoing treatment. The agitating member rises above the surface of the bath for periods of time adequate for the cooling of the grid to such degree that its working efficiency is not impaired through substantially continuous use. With the use of materials such as cast iron

for the puddling apparatus, it is necessary to have a period of cooling substantially equal to the period of contact with the hot metal in order to prevent the undue heating of the puddling apparatus and the alloying of the same with the bath of molten aluminum, or other metal.

In the form of construction illustrated in Fig. 10, a grid 131 of somewhat modified form is shown wherein the arms 132 are provided at their ends with sections 133 of an outer flange which is thus not continuous, in order that fracture of the grid will not occur through undue expansion of the narrow marginal members.

It has heretofore been proposed to puddle type metal and like low melting point metals by means of mechanism constantly immersed within the molten bath and this is commercially practicable because of the low temperatures involved. Where, however, high temperatures from 1200° to 1600° F. are present in the furnace it will be readily understood that the ordinary mechanism for agitating the molten bath could not be employed as it would not remain in operative condition for an adequate period to warrant its installation. Furthermore, the constant contact of an iron vessel with a bath of molten aluminum or of iron stirring devices with such bath tends to alloy said iron with the aluminum introducing a factor which interferes with the quality of the finished product, as iron in excess is very harmful to the physical characteristics of the aluminum for fabricating purposes.

The present furnace, therefore, presents a structure wherein a non-metallic chamber is provided for the heating of readily oxidizable metals, and metals which readily form ferrous alloys, and at the same time is of adequate strength and equipped with safety chambers beneath the same so that no harmful or dangerous elements are involved in the commercial utilization of the same.

While the ducts connecting the chambers at either side of the puddling chamber with the puddling chamber have been shown adjacent the base of each of the chambers, and the floors of said chambers have been substantially on an equal level, it is to be understood that under certain circumstances it may be found desirable to have a supply chamber for the molten mass at a higher level than that of the puddling chamber and the casting chamber for the device at a lower level. Such variations are to be understood as coming within the scope of any claims of sufficient breadth not to specifically exclude the same.

The product resulting from the working and sub-dividing of the molten metal mass, particularly of aluminum and its alloys has been found to be of a tenacity superior to that of any product which might be formed by other methods from the same identical class of material. Thus, if secondary material such as borings, turnings, filings, skimmings, and the like, are melted in an ordinary melting pot under the present practice, a large portion of such product will escape in the form of oxides and gases and the actual aluminum recovered will be but a small percentage of that found to be present in the raw material. With the applicant's apparatus and method of treatment, however, it has been found that the recovery of aluminum in the final product can be made equal to that shown to be in the raw material even when secondary material, carrying as low as fifteen (15) percent of aluminum is employed.

Furthermore, through the use of this appara-

80

tus and method, metal in fabricated form can be produced in a single operation, from very low grade raw material. The metal, whether cast into finished articles or into ingots, after the 5 thorough puddling it received in the apparatus described, shows a great tenacity and a fine quality of grain such as can be produced only under most perfect conditions with substantial laboratory facilities as compared with high speed commercial production.

10 Other modes of applying the principle of my invention may be employed instead of the one explained, change being made as regards the means and the steps herein disclosed and the 15 forms of the product resulting therefrom, provided those stated by any one of the following claims or their equivalents be employed or embodied therein.

I therefore particularly point out and distinctly claim as my invention:

20 1. An apparatus of the character described having in combination a furnace structure having agitating, melting, and casting chambers, a fenestrated grid substantially filling said agitating chamber transversely and adapted to be moved through the molten metal in said chamber to sub-divide the same and to act thereon with friction and impact to disrupt oxide coatings over particles of metal and to deoxidize the 25 molten mass and passageways below the surface of the metal bath communicating with said melting and casting chambers and connecting each, individually with said melting chamber.

30 2. An apparatus of the character described having in combination a furnace structure hav-

ing a plurality of chambers, a fenestrated grid substantially filling one of said chambers transversely and adapted to be moved through the molten metal in said chamber to agitate and sub-divide the same and to act thereon with friction and impact to disrupt oxide coatings over particles of metal and to deoxidize the molten mass, another of said chambers associated with said agitating chamber to serve as a supply chamber for molten metal for such agitating chamber, a chamber on the opposite side of said agitating chamber to receive the metal treated therein, and passageways for connecting said melting chamber selectively with either adjacent chamber.

35 3. A grid for use in a furnace chamber to produce friction and impact upon the molten metal contents of said chamber, comprising a body member of relatively greater width and breadth than thickness and having radial arms free at their outer ends providing a plurality of passageways through said member through which the metal in the chamber is to be forced.

40 4. A rectangular grid for use in a furnace chamber to produce friction and impact upon the molten metal contents of said chamber, comprising a body member of relatively greater width and breadth than thickness and having radial arms carrying at their free ends terminal members providing in effect an interrupted rectangular grid margin, and forming a plurality of passageways through said member through which the metal in the chamber is to be forced.
